CONTAINER PART LEAKAGE TESTING MACHINE

Herbert Schrader, Wheeling, W. Va., assignor to
 Continental Can Company, Inc., New York,
 N. Y., a corporation of New York

Application April 23, 1941, Serial No. 389,997

17 Claims. (Cl. 73—51)

The invention relates generally to vacuum testing apparatus and primarily seeks to provide a novel machine structure in which vacuum testing can be efficiently carried out to determine if containers or container parts are leakproof.

Obviously sheet metal or similar containers designed for the packaging of foods and beverages should be leakproof, and this is particularly true if the products are packaged in vacuo, because if air is permitted to leak into the sealed containers the whole purpose of the vacuum packing is defeated. It is the purpose of the present invention to provide a machine structure in which cans or can parts can be quickly and conveniently tested in order to determine if they are proof against such leakage, and in which means is included for delivering leakproof and leaky cans or can parts at different places.

Another object of the invention is to provide a machine of the character stated which is particularly adapted for testing the coniform top pieces of cans which, before assembly with the main can body portions, are open at both ends.

Another object of the invention is to provide a machine structure of the character stated including a traveling carrier, a plurality of can end receiving pockets on said carrier, means for delivering can ends to the pockets by gravity and for similarly discharging tested ends from said pockets, end closure walls engageable with the opposite ends of a can end in each pocket for sealing said opposite ends, means for momentarily pressing said walls in contact with said opposite ends to seal the same, means for drawing and sealing a vacuum in said can end during said pressure application, spring means subservient to said vacuum but effective upon leakage of air into a leaky can end for forcing the engaging closure walls apart, and means for forcing apart closure walls which have for a proper test interval held the vacuum in each leakproof end.

With the above and other objects in view that will hereinafter appear, the nature of the invention will be more fully understood by following the detailed description, the appended claims, and the several views illustrated in the accompanying drawings.

In the drawings:

Figure 1 is a side elevation of a machine embodying the invention.

Figure 2 is an end elevation, parts being broken away.

Figure 3 is an enlarged detail cross sectional view taken through the axis of one of the tester units and the rotor rim on which it is mounted.

Figure 4 is a plan view of the parts illustrated in Figure 3, parts being broken away and in section.

Figure 5 is a left end elevation of the parts illustrated in Figure 3.

Figure 6 is a right end elevation of the parts illustrated in Figure 3, parts being broken away.

Figure 7 is a view similar to Figure 3 illustrating a modified form of the invention.

10 In the machine herein illustrated as an example of embodiment of the invention, there is included a base 5 which supports upstanding frame standards 6 disposed in parallel spaced relation on said base in the manner illustrated 15 in Figures 1 and 2 of the drawings. A cross shaft 7 is rotatably supported in bearings 8 mounted on the standards 6, and a large rotor 9 is supported on said shaft. The rotor includes a hub 10, radial spokes 11, and a rim 12 the peripheral 20 surface 13 of which is ground and lapped for a purpose that will later become apparent.

The rotor rim 12 is provided with a plurality of transverse bores 14 which are disposed in parallel relation and equidistantly spaced about 25 said rim in the manner best illustrated in Figure 1. Each of the bores 14 communicates with the ground and lapped peripheral surface 13 of the rotor through a radial port 15.

A large spur gear 16 is secured upon the shaft 30 7 and is driven by a small spur gear 17 mounted on a stub shaft 18 rotatably supported on the machine base and which also carries a worm wheel 19 to which rotation is imparted by a worm wheel 20 driven by power transmitting 35 connections 21 from the motor 22 also supported on the base.

A frame standard extension 23 is provided at one side of the machine and carries a bracket 24 on which is mounted a vacuum head 25 having 40 a spring-pressed, arcuate shoe portion 26 which is ground and lapped for very close sliding contact with the peripheral surface 13 of the rotor. The shoe 26 includes a vacuum duct 27 which is connected, as at 28, with any suitable source 45 of vacuum (not shown), and it will be obvious that as the rotor turns, the individual ports 15 extending through the peripheral surface 13 will be successively brought into communication with the shoe duct 27 and the vacuum source.

50 An oiler plate 29 is supported at a downward and inward inclination on a bracket 30 secured to the head 25, and the plate is equipped with a felt oil collector 31 onto which oil is permitted to drip from an oil cup 32 supported, as at 33, on said head.

A tester unit generally designated 34 is removably mounted in each of the rotor bores 14 in the manner clearly illustrated in Figures 1, and 3 through 6 of the drawings.

Each of the tester units 34 comprises a plate-like body 35 having a cylindrical extension 36 shaped to snugly fit a rotor bore 14 and equipped with a vacuum chamber 37 at one end and a spring chamber 38 at the other end, said chambers being separated by a partition wall 39.

The partition wall of each tester unit is provided with ports 40 communicating between the chambers 37 and 38. These ports are normally closed by a valve 41 having a yieldable sealing face 42 presented for engagement with the wall 39, said valve being carried on a plunger 43 which is guided in an aperture 44 in the wall 39 and in an aperture 45 in an end closure cap 46 removably secured, as at 47, on the respective extension 36. The plunger extends beyond the closure cap as at 48 in the manner clearly indicated in Figures 3 and 4 and carries an abutment head within the spring chamber. A spring 49 encircles the plunger between the abutment wall 39 and the abutment head 48 and yieldably holds the valve 41 seated in the manner illustrated in Figure 3. Each rotor rim port 15 communicates with the spring chamber 38 in the respective tester unit through a registering port 50 formed in the cylindrical projection 36 of the particular unit.

The vacuum chamber 37 in each tester unit is surrounded by a recess 51 in which is mounted a yieldable sealing wall or ring 52, and a flange extension 53 is provided surrounding the ring 52 at three sides, namely, at each side of the center thereof and inwardly of the center. Each such flange is, therefore, opened toward the periphery of the rotor, and this flange is grooved, as at 54, to receive the base flange extension 55 of a coniform can top 56, said coniform can top terminating in a pouring mouth 57 which extends slightly beyond the flange 53 in the manner clearly illustrated in Figures 3 and 4 of the drawings.

The plate-like body 35 of each tester unit is angle-bent at the inner portion thereof to provide a bracket portion 58, and each bracket portion 58 provides a pivotal support, as at 59, for a lever 60, said lever being pivoted intermediately of its ends. Each lever 60 carries a roller 61 at its inner end and has limited pivotal connection at its outer end, as at 62, with a closure head 63 equipped with a yieldable sealing wall or insert 64 which is engageable in sealing contact with the pouring spout 57 of a cone top being tested in the manner illustrated in Figures 3 and 4.

A stem 65 is threadably adjustable through the tester body 35, as at 66, and is secured in place by a jam nut 67. The free end of each stem 65 passes through an aperture 68 in the respective lever 60 and carries an abutment head 69 spaced a distance to the right of the lever 60 as viewed in Figure 3. A compression spring 70 is coiled about the stem 65 between the abutment head 69 and the respective lever 60 and constantly tends to swing the lever outwardly, or in a direction for moving the sealing head or wall 64 out of contact with the cone top pouring throat 57. The distance to which the spring can thus move the lever 60 is limited by an adjustable abutment means 71.

It is to be understood that the rotor is continuously rotated, and while it is so rotating, 75

cone tops 56 roll through the gravity feed chute 72 and are deposited one by one into the receiving pockets or grooves 54 in the tester units as said tester units are successively presented at the receiving station best illustrated in Figure 1. The rotor moves rather slowly, and since the cone tops are deposited in the receiving pockets as the pockets are moved upwardly past the horizontal position, the cone tops are retained in the pockets by gravity action as they move away from the receiving station. As each tester unit comes opposite the vacuum head 25, the lever roller 61 of the respective lever 60 engages a stationary cam 73 which serves to momentarily press the sealing wall or head insert 64 in tight contact with the respective cone top pouring mouth 57, this pressure also serving to tightly seat the base 55 of the cone top against the stationary sealing wall 52 in the manner clearly illustrated in Figure 3 of the drawings. While the respective cone top 56 is thus clamped between the sealing walls 64 and 52 by applied pressure, the particular valve plunger 43 engages a stationary roller 74 supported on an extension 75 of the vacuum head 25. This engagement of the plunger 43 opens the valve 41 and momentarily affords communication between the chambers 38 and 37. During the brief interval of this communication between the chambers, the respective port 15—50 will be in communication with the vacuum source 27, 28 and a vacuum will be drawn in the chamber 37 and the cone top 56 and sealed therein by immediate closing of the valve 41.

35 The vacuum drawn and sealed in the chamber 37 and the cone top 56 is stronger than the compression spring 70, and the thus subservient spring 70 is unable to force the sealing wall or head 64 away from the cone top mouth 57.

40 It will be obvious that if the particular cone top 56 being tested is leakproof, that is, devoid of any pin holes or other openings through which air might pass into the sealed chamber within, the pressure of the surrounding atmospheric air will continue to hold the sealing wall 64 in sealing contact with the cone top.

45 In the case of any cone top which is leaky, atmospheric air will find its way into the interior of the cone top and the chamber 37, and as soon as the vacuum is thus destroyed to a sufficient degree to render the particular compression spring 70 dominant, said spring will force the lever 60 outwardly, displacing the sealing wall 64 and relieving the clamped condition of the particular cone top between the walls 64 and 52, and the cone top will be free to fall out of the pocket of the testing unit into a discharging runway 76. If it is desired that the runway 76 be positioned at the same side of the machine with the feed-in runway 72, a retaining guard 77 may be provided to determine the place of discharge in the manner illustrated in Figure 1.

50 All cone tops which properly stand the test, that is, tops which are not leaky, retain the vacuum and it is necessary to break the vacuum and to mechanically displace the sealing walls 64 and release these perfect cone tops. This is accomplished by a stationary roller 74a which engages the plungers in the manner shown in Figure 2 for opening the valves 41 to permit air at atmospheric pressure into the vacuum chambers 37 through the ports 15, 50, 40 and relieve the vacuum therein, and by a stationary cam 78 which engages the lever rollers 61 in a manner for displacing the sealing heads 63, 64 so as to free the

properly tested cone tops in time to permit them to discharge, by gravity, into the discharge runway 19.

While the machine herein disclosed is particularly designed for the testing of cone tops such as are illustrated in Figures 3 and 4 of the drawings, it is to be understood that the invention is not limited to this specific use, and the invention applies as well to machine structures adaptable for the testing of cylindrical containers open at one or both ends. An example of this modification of the invention is illustrated in Figure 7 of the drawings in which the invention is applied to equipment for testing containers having cylindrical bodies 80 which may be open or closed as at 81 at one end, and open only at the center at the other end as at 82.

In this modification of the invention the tester units are identical in construction and operation with those previously described except that the angle bent bracket portions 83 are made longer so as to accommodate the greater length of the container unit being tested. The movable sealing wall 84 and its yieldable facing 85 must be made larger as illustrated in Figure 7, and the fixed wall of the tester unit is formed as illustrated to support an apertured center engaging sealing wall or plug 86. Since the operation of this modified form of the invention is identical to that previously described, repetition of this description is thought to be unnecessary.

It is of course to be understood that the details of structure and arrangement of parts may be variously changed and modified without departing from the spirit and scope of my invention.

I claim:

1. In a machine of the character described, a rotor; a plurality of tester units carried by said rotor, each including a peripherally open pocket for receiving a container unit open at both ends, a pair of unit clamping and open end sealing walls engageable with the unit ends to secure said units against ingress of air, means acting through one wall of each pocket for drawing and holding a vacuum in said pocket, said walls being held against said unit ends by differential air pressure alone, whereby leakproof units will be held by said walls and said walls will be free to allow leaky container units to fall by gravity from the pockets, and means for admitting air at atmospheric pressure into leakproof container units in the pockets in which they are held and for releasing said units from said pockets after they have remained in said pockets throughout a suitable test interval, thereby to allow said leakproof container units to fall out of the pockets.

2. A hollow container testing unit comprising a pocket for receiving a container having an opening at at least one end, end closure members engageable with opposite ends of a container-to-be-tested for holding the container in place and for sealing it against ingress of atmospheric air, valve means through which a vacuum can be drawn in a held container, and spring means constantly tending during the testing of a can to force said closure members apart, said spring means being subservient to the drawn vacuum but effective upon leakage of air into a leaky container for forcing said closure members apart and releasing said container.

3. A hollow container testing unit comprising a pocket for receiving a container having an opening at at least one end, end closure members engageable with opposite ends of a container-to-be-tested for holding the container in place and

for sealing it against ingress of atmospheric air, valve means through which a vacuum can be drawn in a held container, and spring means subservient to the drawn vacuum but effective upon leakage of air into a leaky container for forcing said closure members apart and releasing said container, said valve means also having means for admitting air at atmospheric pressure into a container which has held the vacuum throughout a proper test interval to thereby render the spring effective to force said closure members apart.

4. A hollow container testing unit comprising a pocket for receiving a container having an opening at at least one end, end closure members engageable with opposite ends of a container-to-be-tested for holding the container in place and for sealing it against ingress of atmospheric air, valve means through which a vacuum can be drawn in a held container, spring means constantly tending during the testing of a can to force said closure members apart, said spring means being subservient to the drawn vacuum but effective upon leakage of air into a leaky container for forcing said closure members apart and releasing said container, and means for limiting the distance to which the spring can force the closure members apart.

5. A hollow container testing unit comprising a pocket for receiving a container having an opening at at least one end, end closure members engageable with opposite ends of a container-to-be-tested for holding the container in place and for sealing it against ingress of atmospheric air, valve means through which a vacuum can be drawn in a held container, spring means subservient to the drawn vacuum but effective upon leakage of air into a leaky container for forcing said closure members apart and releasing said container, said valve means also having means for admitting air at atmospheric pressure into a container which has held the vacuum throughout a proper test interval to thereby render the spring effective to force said closure members apart, and means for limiting the distance to which the spring can force the closure members apart.

6. A testing unit for testing cone tops open at both ends, said unit comprising a cone top receiving pocket, clamping walls engageable with opposite ends of a cone top for sealing it against ingress of atmospheric air, valve means through which a vacuum can be drawn in a clamped cone top, spring means subservient to the drawn vacuum but effective upon leakage of air into a leaky cone top for forcing said clamping walls apart and releasing said containers, and means for bringing about the release of cone tops which hold the vacuum throughout a proper test interval.

7. A hollow container testing unit comprising a body having a pocket therein for receiving a container which is open at at least one end and a mounting hub including a chamber therein, a sealing ring on said body engageable by an end of a container-to-be-tested for sealing the same against ingress of atmospheric air, a pivotally mounted clamping wall opposed to said body and engageable with the other end of the container for holding the container against the ring, spring means between the wall and the body and constantly tending to move the wall away from the body, said chamber having means for communicating with a source of vacuum or with atmospheric air, said body having a port for communicating between the chamber and the interior of

a container sealed against the ring, and valve means for controlling said port.

8. A testing unit for open ended cone tops, said unit comprising a body having a pocket therein for receiving a cone top and a sealing ring engageable with the base of the cone top and a port opening within said ring, a unit mounting hub attached to said body and having a chamber therein and means for communicating with a source of vacuum or with atmospheric air, valve means controlling said port, a clamping and sealing head opposed to said body and engageable in holding and sealing contact with the pouring mouth of the cone top, a lever carrying said head and pivoted to said body, and spring means interposed between the lever and the body and constantly tending to move the head away from the body, said lever being extended beyond its pivot and being provided with means engageable in one direction for moving the head against a cone top mouth and in the other direction for positively moving the head away from a cone top mouth.

9. A testing unit for open ended cone tops, said unit comprising a body having a pocket therein for receiving a cone top and a sealing ring engageable with the base of the cone top and a port opening within said ring, a unit mounting hub attached to said body and having a chamber therein and means for communicating with a source of vacuum or with atmospheric air, valve means controlling said port, a clamping and sealing head opposed to said body and engageable in holding and sealing contact with the pouring mouth of the cone top, a lever carrying said head and pivoted to said body, spring means interposed between the lever and the body and constantly tending to move the head away from the body, said lever being extended beyond its pivot and being provided with means engageable in one direction for moving the head against a cone top mouth and in the other direction for positively moving the head away from a cone top mouth, and means for limiting movement of the head away from the body.

10. In a machine for testing cone tops each having an open pouring mouth and an open base, a traveling carrier, a plurality of cone top receiving pockets on said carrier, means for delivering cone tops to the pockets, end closure walls engageable with the mouth and base respectively of each cone top in each pocket for sealing said cone top against ingress of atmospheric air, means for momentarily pressing said walls in contact with said unit ends, means for drawing and sealing a vacuum in said cone top during said momentary pressure application, spring means subservient to said vacuum but effective upon leakage of air into a leaky cone top for forcing said walls apart and releasing said cone top, and means for effecting separation of closure walls which have for a proper test interval held the vacuum in each leak-proof cone top.

11. In a machine for testing cone tops each having an open pouring mouth and an open base, a traveling carrier, a plurality of cone top receiving pockets on said carrier, means for delivering cone tops to the pockets, end closure walls engageable with the mouth and base respectively of each cone top in each pocket for sealing said cone top against ingress of atmospheric air, means for momentarily pressing said walls in contact with said unit ends, means for drawing and sealing a vacuum in said cone top during said momentary pressure application, spring means subservient to said vacuum but effective upon leakage of air

into a leaky cone top for forcing said walls apart and releasing said cone top, and means for effecting separation of closure walls which have for a proper test interval held the vacuum in each leak-proof cone top, said carrier comprising a continuously moving rotor having a tester unit mounting periphery, and said vacuum drawing means including a short length stationarily supported chambered shoe, spring pressed against said rotor periphery for successive cooperation through connecting porting with the individual cone top receiving pockets.

12. In a machine for testing cone tops each having an open pouring mouth and an open base, a traveling carrier, a plurality of cone top receiving pockets on said carrier, means for delivering cone tops to the pockets, end closure walls engageable with the mouth and base respectively of each cone top in each pocket for sealing said cone top against ingress of atmospheric air, means for momentarily pressing said walls in contact with said unit ends, means for drawing and sealing a vacuum in said cone top during said momentary pressure application, spring means subservient to said vacuum but effective upon leakage of air into a leaky cone top for forcing said walls apart and releasing said cone top, and means for releasing the vacuum in leak proof cone tops which have been sealed by said wall contact throughout a proper test interval.

13. In a machine for testing cone tops each having an open pouring mouth and an open base, a traveling carrier, a plurality of cone top receiving pockets on said carrier, means for delivering cone tops to the pockets, end closure walls engageable with the mouth and base respectively of each cone top in each pocket for sealing said cone top against ingress of atmospheric air, means for momentarily pressing said walls in contact with said unit ends, means for drawing and sealing a vacuum in said cone top during said momentary pressure application, spring means subservient to said vacuum but effective upon leakage of air into a leaky cone top for forcing said walls apart and releasing said cone top, and means for effecting separation of closure walls which have for a proper test interval held the vacuum in each leak-proof cone top, said carrier comprising a continuously moving rotor having a tester unit mounting periphery, and said vacuum drawing means including a short length stationarily supported chambered shoe spring pressed against said rotor periphery for successive cooperation through connecting porting with the individual cone top receiving pockets and a spring pressed vacuum sealing valve associated with each said pocket, means for unseating and opening the vacuum sealing valve associated with each pocket containing a leakproof cone top after a suitable testing interval to release the vacuum and permit the spring means to separate the walls and release the tested cone tops.

14. In a cone top testing machine, a rotor, a plurality of tester units carried by said rotor, each having a vacuum chamber therein surrounded by a cone top base engaging and sealing wall ring, a movable wall opposed to said ring and engageable in sealing contact with the cone top pouring mouth, and a support for the inner edge of a cone top, a spring pressed valve normally sealing each chamber against ingress of air, means for momentarily unseating each valve and drawing a vacuum in each chamber and a cone top engaged by the respective wall ring and opposing wall, whereby differential air pressure will

hold the wall ring and opposed wall in vacuum sealing contact with the cone top, only if it is leakproof and leakage of air at atmospheric pressure into leaky cone tops through leak openings therein will equalize the air pressure within and without the cone top and vacuum chamber and relieve the drawn vacuum and release the pressure contact of said opposing wall and wall ring to free the leaky cone top or tops, and means for unseating said valves to admit atmospheric air and free leakproof cone tops.

15. In a cone top testing machine, a rotor having a tester unit mounting periphery, a plurality of tester units carried by said rotor periphery, each having a vacuum chamber therein surrounded by a cone top base engaging and sealing wall ring, a movable wall opposed to said ring and engageable in sealing contact with the cone top pouring mouth, and a support for the inner edge of a cone top, a spring pressed valve normally sealing each chamber against ingress of air, means for momentarily unseating each valve and drawing a vacuum in each chamber and a cone top engaged by the respective wall ring and opposing wall, whereby differential air pressure will hold the wall ring and opposed wall in vacuum sealing contact with the cone top only if it is leakproof and leakage of air at atmospheric pressure into leaky cone tops through leak openings therein will equalize the air pressure within and without the cone top and vacuum chamber and relieve the drawn vacuum and release the pressure contact of said opposing wall and wall ring to free the leaky cone top or tops, and means for unseating said valves to admit atmospheric air and free leakproof cone tops, said vacuum drawing means including a short length spring pressed chambered shoe engaging said rotor periphery for successive cooperation through connecting porting with said tester unit chambers.

16. In a cone top testing machine, a rotor, a plurality of tester units carried by said rotor, each having a vacuum chamber therein surrounded by a cone top base engaging and sealing wall ring, a movable wall opposed to said ring and engageable in sealing contact with the cone top pouring mouth, and a support for the inner edge of a cone top, a spring pressed valve normally sealing each chamber against ingress of air, means for momentarily unseating each valve and drawing a vacuum in each chamber and a cone top engaged by the respective wall ring and opposing wall, whereby differential air pressure will hold the wall ring and opposed wall in vacuum sealing contact with the cone top only if it is leakproof and leakage of air at atmospheric

pressure into leaky cone tops through leak openings therein will equalize the air pressure within and without the cone top and vacuum chamber and relieve the drawn vacuum and release the pressure contact of said opposing wall and wall ring to free the leaky cone top or tops, short length stationary cam means for holding each opposing wall against the respective cone top for only a short interval while the vacuum is being drawn and secured therein, said opposing wall contact with the cone top being maintained at other times solely by atmospheric pressure, means for unseating each valve to atmospheric air after a testing interval, and spring means for separating each said opposing wall and the cooperating wall ring as the respective valve is unseated.

17. In a cone top testing machine, a rotor, a plurality of tester units carried by said rotor, each having a vacuum chamber therein surrounded by a cone top base engaging and sealing wall ring, a movable wall opposed to said ring and engageable in sealing contact with the cone top pouring mouth, and a support for the inner edge of a cone top, a spring pressed valve normally sealing each chamber against ingress of air, means for momentarily unseating each valve and drawing a vacuum in each chamber and a cone top engaged by the respective wall ring and opposing wall, whereby differential air pressure will hold the wall ring and opposed wall in vacuum sealing contact with the cone top only if it is leakproof and leakage of air at atmospheric pressure into leaky cone tops through leak openings therein will equalize air pressure within and without the cone top and vacuum chamber and relieve the drawn vacuum and release the pressure contact of said opposing wall and wall ring to free the leaky cone top or tops, stationary cam means for holding each opposing wall against the respective cone top while the vacuum is being drawn and secured therein, means for unseating each valve to admit atmospheric air after a testing interval, spring means for separating each said opposing wall and the cooperating wall ring as the respective valve is unseated, said rotor having individual vacuum ports communicating with the respective chambers under control of said spring pressed valve and extending through the periphery thereof, and said vacuum drawing means including a short length spring pressed vacuum chambered shoe engaging the periphery of the rotor for successive cooperation with said tester unit chambers through said ports.

HERBERT SCHRADER.
